ATTORNEY

UNITED STATES PATENT OFFICE.

PETER C. CLEMMENSEN, OF ATLANTIC, IOWA.

TOBACCO-CAN.

1,280,165.

Specification of Letters Patent. Patented Oct. 1, 1918.

Application filed November 30, 1917. Serial No. 204,756.

To all whom it may concern:

Be it known that I, PETER C. CLEMMENSEN, a citizen of the United States, residing at Atlantic, in the county of Cass and State of Iowa, have invented certain new and useful Improvements in Tobacco-Cans, of which the following is a specification.

This invention relates to receptacles, and it relates more particularly to an improvement in tobacco receptacles or cans.

One of the objects of this invention is to provide a false bottom for the receptacle, which may be raised so as to bring the tobacco into convenient position to be reached and grasped by the fingers of the user.

Another object is to provide a device of this character which is easy to manipulate and which does not interfere with the opening and closing of the box, and does not interfere with the removal or re-placing of the box in the pocket of the user.

Another object of the invention is to provide a device of this character which is so simple of construction that it may be manufactured at a minimum cost.

Another object is to provide a device of this character which may be formed integrally from a single blank of sheet metal, as an article of manufacture, and which is of such form that it may be nested with a number of similar devices for convenience in shipping these articles to manufacturers of tobacco receptacles of ordinary construction, and for convenience in storing the devices.

Another object of the invention is to provide for quickly and easily removing such portions of the device that have served their purpose and would be in the way if not removed.

Other objects and advantages may become apparent to persons who read the following details of description in connection with the accompanying drawings in which—

Figure 1 is a perspective view illustrating a tobacco box or can of ordinary construction with my improved attachment in the position it would occupy after a portion of the tobacco has been removed, and the remainder raised in the box.

Fig. 2 is an end view of a slightly modified form and embodiment of my invention.

Fig. 3 is a perspective view of a tobacco elevator which constitutes the attachment

forming the subject matter of my invention, this figure also showing a slight modification.

Fig. 4 is a fragmental sectional detail view of an element of the attachment.

Referring to these drawings in detail, in which similar reference characters correspond with similar parts throughout the several views—

The tobacco box A, having the lid B secured thereto by the hinge C, being of ordinary construction, is not claimed *per se*. The attachment of elevator illustrated separately in Fig. 3 comprises the false bottom or plate 5 having stiffening ribs or flanges 6 extending at right angles therefrom, and continuing from end to end thereof, the plate 5 also having relatively narrow extensions 7 at its opposite ends, these extensions being primarily of a length somewhat greater than the depth of any box or receptacle to which the elevator may be attached. The elements 7 are each formed with a plurality of horizontal or laterally extending rows of perforations or indentations 8 for the purpose of providing weakened portions at which the elements 7 may be quickly and easily bent and broken off at a line on one of the elements which corresponds with a similar line on the other of the elements, for effecting a purpose which will hereinafter appear.

When the device is first applied to the box A before the latter is filled with tobacco or other contents, the flanges 6 rest upon the bottom *a*, (except in the modified form shown in Fig. 2) the free ends of the elements 7 are then bent down over two opposite edges of the box as indicated at 9, and they may be bent either along the respective rows of apertures, as indicated in Fig. 1 or at any portion between two adjacent rows; or, if desired, the free ends of the elements 7 may be broken off respectively at the row of perforations adjacent to the top of the box, so that these elements terminate within the box; or else they may be turned inward after the tobacco is placed in the box, so that these ends extend over the tobacco and provide manipulating elements whereby the elevator may be raised. Moreover, in forming this elevator, the flanges 6 may be turned in the direction opposite from that which is illustrated in Figs. 1 and 3, or in the same direc-

tion of the supporting elements 7, Fig. 2, thereby somewhat reducing the cost of manufacture while providing room for more tobacco in the box. Each construction above described has its advantage over the other construction, and so the device may be varied in this respect according to the desire of the manufacturer. When the tobacco is being used from the box, and the distance from the top of the box to the top of the tobacco becomes so great as to be inconvenient to the grasp of the user, the manipulative elements at the ends of the supporting strips 7 may be grasped and pulled for raising the tobacco toward the top of the box. When the tobacco is sufficiently raised, the strips may be bent over the edges of the box, as shown at 9 along the corresponding rows of apertures 8, so as to support the false bottom 5 in its elevated position. The elevator being formed of very thin sheet metal, the flanges of the lid B and the corresponding sides of the box A will yield sufficiently to allow the lid to close over the down-turned free ends 25 of the supporting strips 7. The distance between the rows of perforations 8 is substantially the same as the width of the flanges of the lid B, so that the lower edges of the lid-flanges register with certain of the rows of perforations or indentations. It will be seen therefore, that when the supporting strips are bent downward as shown at 9, the flanges of the lid B serve to hold the adjacent portions of the supporting strips and to act as 35 guides along which the respective rows of perforations extend, and thereby coöperate with the weakened portions of the strips 7 for effecting the quick and easy removal of the superfluous end portions of the latter 40 when they are bent by the user.

Although I have described this device in minute detail, it is to be understood that my invention is not limited to these exact details of construction, and that I may make such 45 changes that do not constitute a departure

from the inventive idea disclosed herein and in the appended claims.

What I claim as my invention is:

1. As an article of manufacture, a blank of sheet metal formed with a relatively wide intermediate portion having parallel stiffening elements formed thereon and having a relatively narrow extension at each end adapted to be bent at right angles to said intermediate portion and into parallel relation with one another, each of said extensions being relatively long and narrow and being formed with weakened portions extending laterally there-across, substantially as described and for the purpose specified. 60

2. As a new article of manufacture, a supporting device formed from a blank of thin sheet metal so as to provide a supporting plate having stiffening flanges extending along two opposite sides thereof and having supporting strips extending from the other two opposite sides thereof and bent so as to be substantially parallel with one another and at an angle to said supporting plate, each of said supporting strips being provided with a plurality of substantially equi-spaced weakened portions adapted to be bent for providing supporting hooks and adapted to be broken for removing superfluous material. 70

3. An oblong plate, having stiffening elements at its longitudinal edges consisting of bent edge portions of the plate, and having integral narrow strips at the ends of the plate extending at a right angle thereto, and 80 parallel to each other, said strips having transversely weakened lines in coincident relation. 75

In testimony whereof I affix my signature in presence of two witnesses.

PETER C. CLEMMENSEN.
